PORTABLE CLOTHES LINE UNIT

Bayar Goodman, Los Angeles, Calif., assignor to Wilshire Manufacturing Company, Los Angeles, Calif., a partnership

Application August 23, 1954, Serial No. 451,414

17 Claims. (Cl. 211—119.15)

This invention relates to a portable clothes line unit and more particularly to a portable clothes line which can be wound upon a drum for extension or retraction and which can be easily mounted upon a supporting structure.

Previous devices of this nature have required complicated latching devices in order to tension the clothes line after the clothes line has been extended. Also, when these prior devices utilize more than one line, there has been no means in which to compensate for differences in the length of the individual lines and for differences in tension on the individual lines. By the present invention, a plurality of lines can be mounted upon a single spring biased drum and the end of each line is connected to an equalizer bar which is mounted at a desired distance from the drum after the lines have been extended. In order to adjust for differences in length and tension between the various lines, the lines are connected together in pairs which pass around pulleys in the equalizer bar and the equalizer bar is pivotally mounted at one point so that the tension on one line can be distributed to all of the lines. Thus, the two lines of any pair will have equal tension even though one line is slightly longer than the other and in the event that the equalizer bar assumes an angle to the lines while they are being pulled from the drum, the tension on all of the lines will be maintained. The lines are placed in tension by the manual rotation of the drum by a simple pivoted lever which has a pin that can be inserted into any one of a number of openings in order to maintain the drum in position to hold the lines in tension and it is only necessary to pivot this lever when it is desired to release the tension in the lines.

It is therefore an object of the present invention to provide a portable clothes line unit having a plurality of clothes lines wound around a spring biased drum which is of simple and economical construction.

Another object of the present invention is to provide a portable clothes line unit in which a plurality of clothes lines are wound upon a spring biased drum and are connected together in pairs around pulleys of an equalizer bar so that the tension on each line can be maintained and the lines will not become tangled on the drum.

Another object of the invention is to provide a portable clothes line unit in which the individual clothes lines can be locked in tension by a simple locking device.

A further object of the invention is to provide an equalizer bar to which all of the individual lines are secured around pulleys and so that the lines are connected together in pairs.

A still further object of the invention is to provide an equalizer bar which is pivotally mounted when the lines are in extended position so as to allow the tension on the lines to be equalized.

These and other objects of the invention, not specifically set forth above, will become readily apparent from the accompanying specification and drawings in which:

Fig. 1 is a side elevational view of the portable clothes line unit illustrating the manner in which the drum and

2

equalizer bar are mounted in spaced apart relationship with the individual lines extending therebetween.

Fig. 2 is a front elevational view along line 2—2 of Fig. 1 showing the opening in the housing for receiving the equalizer bar when in retracted position.

Fig. 3 is a horizontal section along line 3—3 of Fig. 2 showing the spring biased drum connected to the tensioning lever.

Fig. 4 is a vertical sectional view of line 4—4 of Fig. 3 showing the pivot construction for the lever.

Fig. 5 is a vertical section along line 5—5 of Fig. 3 showing the mounting bracket for the housing.

Fig. 6 is a top plan view of the drum illustrating the manner in which the individual lines are connected together in pairs around pulleys carried by the equalizer bar.

Fig. 7 is a front elevational view similar to Figure 2 showing the equalizer bar in retracted position and parts broken away to show the lines wound around the drum.

Fig. 8 is a top plan view of a modified form of the bracket to which the equalizer bar is attached.

Referring to Fig. 1, the clothes lines are shown extended between a housing unit 8 and an equalizer bar 9. The equalizer bar has a single opening 10 midway its length which receives a pin 10' carried by arm 11 of a bracket 12. The bracket 12 is secured to any suitable mounting post 13 by means of screws 14 so that the equalizer bar can be restrained when the desired tension is placed upon the individual clothes lines. Referring to Fig. 3, the housing unit 8 has an outer casing 15 which receives at one end a projection 16 of end fitting 17 and the casing can be secured in any suitable manner, such as by screws, to the projection 16. A shaft 18 projects through fitting 17 and into collar 19 which has a circular projection 19' for receiving one end of tube 20. A bolt 20' passes through the shaft 18, collar 19 and tube 20 in order to rigidly secure these members together. The other end of shaft 18 located exteriorly of fitting 17 carries a pin 21 which bears against a stop screw 22 in order to position the shaft 18. The outer casing 15 receives at its other end a projection 23 of end fitting 24 and the projection 23 is secured to casing 15 by any well-known means, such as by screws. A shaft 25 projects through fitting 24 and into a collar 26 which is secured in the other end of tube 20. A disc 27 has a hub 28 which is secured to shaft 25 by means of a roll pin 29 so that the disc 27 moves with shaft 25 which is free to rotate within the collar 26. The disc 27 also has a projection 30 which surrounds the end of tube 20 and collar 26 and one end of spring 31 surrounds this projection. The end of spring 31 is secured to projection 30 by means of screws 32 and 33 which pass between two coils of the spring at a position several coils from the end of the spring. A channel shaped bracket 34 spans the two coils, one on each side of the screw 32, in order to help retain these coils in position and a lock washer 34', such as a star washer, is positioned between the bracket and the head of screw 32. In a similar manner, a channel shaped bracket 35 spans the two coils, one on each side of screw 33, in order to retain the coils in position and a lock washer 35' is positioned between the bracket and the head of screw 33. The spring 31 extends around the tube 20 and the other end passes around projections 36 and 37 of the fitting 19. This other end is secured to projections 36 and 37 by screws 38 and 39, respectively, passing between two coils located at a distance from this end of the spring. Channel shaped brackets 40 and 41 receive the coils of the spring on opposite sides of screws 38 and 39, respectively, in order to aid the screws in holding the end of the spring, and lock washers 40' and 41' are placed between each bracket and the screw head. Since the shaft 18 is prevented from rotating by stop

screw 22, it is apparent that the end of spring 31 secured to collar 19 will be fixed in position and that the spring 31 can be compressed by rotation of shaft 25 and projection 30.

Shaft 18 carries a disc 44 which is positioned within one end of a winding drum 45 and the winding drum is secured to the disc 44 by means of screws 46, which likewise serve to position clamp 47 on the winding drum. The other end of the drum receives disc 27 and is secured thereto by means of screws 48, which also serve to mount clamp 50. The clamps 47 and 50 receive the initial two coils of lines 51 and 52, respectively, and serve to secure the ends of the lines to the drum. Similar clamps 53 and 54 are positioned at equal distances from clamps 47 and 50, respectively, and receive the two initial coils of lines 55 and 56. The coils received by the end clamps 47 and 50 are wound in a direction so that they approach the middle of the winding drum and the clamps 53 and 54 are positioned approximately one-quarter of the length of the drum from each end so that the lines 55 and 56 can wind towards the center of the drum because of the direction in which the initial coils are wound.

A lever arm 57 is pivotally mounted on the end of shaft 25 by means of a bolt 58 which has its head 59 passing through an opening in the hub 60 of the lever to compress a coil spring 60', positioned between the head and the shaft 25, when the other end of the screw is threaded into a lock nut 61. Thus, the bolt 58 serves as a pivot for the lever arm 57 and the force of spring 60' between the head 59 and shaft 25 serves to hold the lever in any tilted position. The diameter of hub 60 is sufficiently larger than the end of the shaft to permit pivotal movement of the lever. The lever has an arm 62 and an arm 63 carrying a pin 64 which is so positioned that it can be inserted into any one of a number of openings 65 in the fitting 24. It is apparent that when the lever 57 is rotated, the winding drum 45 will likewise be rotated since the disc 27 is secured to shaft 25 and the disc 44 is free to rotate upon shaft 18.

In order to support the housing unit 8, a pair of brackets 66 and 67 are secured to a supporting structure 68 by means of screw 69 and the face of each bracket is positioned away from the supporting structure by center flange 70 and side flanges 71. The upper end of the flange face contains an elevated portion 72 having a slit 73. Each of the end fittings 17 and 24 have a projection 74 carrying an end flange 75 and the projection 74 can be inserted into slit 73 so that the flange 75 is retained within the portion 72 of the bracket. Each end fitting also has a projection 76 which bears against the face of the bracket in order to retain the housing unit 8 in upright position.

As illustrated in Figure 2, the housing 15 has an opening 77 along its length in order to receive equalizer bar 9 when the bar is in its retracted position illustrated in Figure 7. The equalizer bar is substantially U-shaped in cross-section and carries four pulleys 79, 80, 81 and 82 which are pivotally mounted in the open side of the bar by pins 83 and are spaced apart in the same distances as clamps 47, 50, 53 and 54. The lines 52 and 56 pass around pulleys 82 and 83, respectively, and are tied together approximately midway of the pulleys so that their junction 84 will be positioned within the equalizer bar. In the same manner, lines 51 and 55 pass around pulley 79 and 80, respectively, and are tied together at point 85 which is located within the equalizer bar.

When the unit is placed in use, the housing unit 8 is supported upon its mounting 68 by the brackets 66 and 67 in the manner previously described and the equalizer bar is held within the opening 77 by the initial spring bias as on the drum 45. This initial spring bias is provided by biasing the spring 31 a given amount before the ends of the individual clothes lines are secured to the equalizer bar. Thus, the coil spring 31 exerts a force on the drum 45 in a direction to wind up the individual clothes lines whether the equalizer bar is in opening 77 or whether it is extended. When the equalizer bar is not extended, the 75

lever 57 will be in the position shown in Figure 7 where in the pin 64 is drawn away from the end fitting 24. When it is desired to extend the clothes lines, the equalizer bar 9 will be pulled away from the housing unit a distance so that the opening 10 can receive the pin 10' of the bracket 12 and the individual lines will unwind from drum 45, thus rotating the drum to increase the spring bias on the drum caused by spring 31. In the extended and unextended positions of the equalizer bar, the spring 31 will continually place a torque upon rod 18 so that pin 21 will engage stop screw 22 and fix the end of the spring secured to collar 19. The force of the spring 31 opposing the withdrawal of the clothes lines is transmitted to drum 45 through disc 27 and the lever 57 will revolve with disc 27 during withdrawal of the lines since it is secured thereto.

While the lines are being extended, the equalizer bar 9 is usually tilted at some angle to the housing unit illustrated by the phantom line position in Figure 6. Because of the fact that lines 51 and 55 and lines 52 and 56 are connected together around pulleys in the equalizer bar, it is possible to maintain the tension on all of these lines regardless of the tilted position of the bar since the connections 84 and 85 can move in one direction or the other 20 to take up slack in any one of the lines. Thus, none of the lines can sag to result in tangling of the lines upon the drum 45. After the lines have been fully extended, the bar 9 is positioned so that opening 10 receives pin 10' and the bar is thus pivotally mounted by the pin. In order to 25 apply increased tension to the lines so that they can support clothes and other items without excessive sagging, the lever 57 is manually rotated in order to rotate drum 45 in a direction to wind the lines upon the drum. After a sufficient tension has been produced, the lever 57 is tilted 30 into the position illustrated in Figure 3 so that the pin 64 will enter the nearest opening 65 in fitting 24. Because of the fact that the coil spring 60' is compressed between the screw head 59 and shaft 25, and because of the friction 35 between the pin 64 and opening 65 caused by the tension on the lines, the lever will remain in locked position. When it is desired to retract the clothes lines, it is only necessary to tip the arm 63 of lever 57 in order to retract the pin 64 from one of the openings 65 and thus permit only the tension of spring 31 to act upon the lines.

During the time that the lines are tensioned for supporting a load, if one of the lines receives a greater load than the other lines, this greater load will be distributed to the other lines because of the manner in which the lines are attached to the equalizer bar. For instance, if line 51 had a considerably heavier load than the other lines, the tension in this line can be distributed to line 55 because of the fact that the two lines are connected together at terminal 85. Also because of the fact that the equalizer bar is pivotally mounted by pin 10' the bar can pivot around the pin and distribute the greater load to lines 52 and 56. 40 If the load is excessive on line 56, the load will be distributed between lines 52 and 56 and will also be transmitted to lines 52 and 56 because of the pivotal mounting of the bar. If each line were rigidly attached to the bar and the bar rigidly supported, this type of load distribution between the lines would not be possible. Referring to the mounting of the housing 8, it is unnecessary to have the arms 76 of end fittings 17 and 24 secured to the mounting brackets since the weight of the housing and all of the torque applied to the housing unit will be in a direction to force the end of arm 76 against the face of the bracket.

A modified bracket 12' is shown in Figure 8 secured to post 13 by means of a U-bolt 86 and nuts 87. The modified bracket is for the same purpose as bracket 12 and is similar in shape. However, when the modified bracket is used, the equalizer bar 9 has a pin 88 rigidly secured thereto mid-way its length and two spaced openings 89 and 90 are positioned in arm 11' at right angles to each other. Thus, with the bracket in the position shown in Figure 8, the pin 88 will be inserted into open-

ing. 89 in order to pivotally mount the equalizer bar. The bracket 12' can also be mounted in the same position as shown in Figure 1, for bracket 12 by rotating the bracket 90 degrees and utilizing screws to secure the bracket to post 13. In this position, the pin 88 will be received by opening 90 in order to pivotably support the equalizer bar.

By the present invention, a novel portable clothes line unit is provided in which tension is continually maintained on each of the lines as the lines are unwound and in which the excessive load on one line can be distributed to the other lines. Also, a novel locking device is provided which is simple in construction and operation and requires no independent latching means. The method of connecting the spring to the winding drum is greatly simplified by the manner in which the ends of the springs are secured. It is obvious that any number of clothes lines can be utilized on a single winding drum and that these lines can be connected together in various manners around pulleys of the equalizer bar to obtain the required tensioning and load distribution. Various other modifications are contemplated by those skilled in the art without departing from the spirit and scope of the invention as hereinafter defined by the appended claims.

What is claimed is:

1. A portable clothes line unit comprising a spring secured at one end to a first end member and at its other end to a rotatable member, a winding drum secured to said rotatable member for rotation therewith and having a plurality of the lines secured in spaced apart positions on its surface, said rotatable member being rotatably supported by a second end member having a series of openings around a circular path concentric with the axis of said rotatable member, means for holding the ends of said lines after being extended from said drum, and a lever pivotally connected to said rotatable member and having a pin adapted for insertion into one of said openings upon said lever being tilted, said lever being rotated to tighten the lines and thereafter tilted to lock the drum against rotation.

2. A portable clothes line unit as defined in claim 1 wherein the ends of said spring are secured to said first end member and said rotatable member by a plurality of screw means passing between two coils of said spring located several coils distant from each end of the spring, and means for holding said two coils in position adjacent said screw means.

3. A portable clothes line unit as defined in claim 1 wherein said rotatable member comprises a shaft and said lever has an enlarged opening for receiving the end of said shaft, said lever being pivotally mounted on the end of said shaft by a bolt and spring means for exerting a force between the head of said bolt and said shaft so that the lever will be held in any tilted position by the force between the bolt head and the shaft.

4. A portable clothes line unit as defined in claim 1 wherein said end members support a casing for the unit, each end member having a first projection carrying a flange, a bracket for each of said end members secured to a supporting structure, said bracket having a raised face portion containing a slit for receiving said first projection with the flange positioned within said raised portion, a second projection for each of said end members positioned below said first projection and bearing upon the face of each of said brackets when said unit is mounted upon said brackets.

5. A portable clothes line unit comprising a spring connected at one end to a fixed member and connected at the other end to a rotatable member, a winding drum rotatably mounted at one end on said fixed member and fixed at the other end to said rotatable member, a plurality of lines secured in spaced apart position on the surface of said drum, an equalizer bar carrying a series of pulleys equal in number to the number of lines and spaced apart the same distance as the lines on the drum,

each line passing around one of said pulleys and being connected to an adjacent line substantially midway between the pulleys for the two lines so that the tension on all of said lines can be maintained regardless of any tilting of the bar relative to the drum.

6. A portable clothes line unit comprising a winding drum carrying a plurality of clothes lines, a rotatably mounted member secured to one end of said drum and a fixedly mounted member rotatably connected to the other end of said drum, a coiled spring mounted with said fixed member and said rotatably mounted member for biasing said drum to rotate in one direction, the bias of said drum increasing as said lines are extended a tensioning lever receiving the end of said rotatably mounted member, said lever having a receiving opening larger than the end of said rotatable member so that the lever can pivot with respect to said end, spring means exerting a force between the head of said bolt and said shaft so that the lever will remain in any tilted position,
- 10 20 a fixed member having a series of openings arranged in a circular path concentric with the axis of said rotatable member, and a pin carried by said lever for insertion into one of said openings after said lever has been rotated to tension said lines.
- 25 7. A locking device for retaining tension on extended lines secured to a rotatable drum, said drum having a support member axially fixed in one end of said drum and a support member axially rotatably supported in the other end of said drum, biasing means interconnected 30 with each of said support members for biasing said drum to rotate in one direction, support means for the first-mentioned, rotatably supporting the first-mentioned support member and second support means for fixedly mounting the second-mentioned support member, support means 35 containing a series of openings concentric with the axis of said drum, a tiltable lever secured to said first-mentioned support member and a pin carried by said lever for insertion into one of said openings after the lines have been tensioned by rotation of the lever.
- 40 8. A portable clothes line unit comprising a plurality of lines secured in spaced apart position on a winding drum, said winding drum having a support member axially fixed in one end of said drum and a support member rotatably supported in the other end of said drum, 45 biasing means interconnected with each of said support members for biasing said drum to rotate in one direction, means connected with the first mentioned support member for rotating said drum and for locking said drum in any desired position, a bar having a pulley for each of said lines with said pulleys spaced apart substantially the same distance as the lines, each of said lines passing around one of said pulleys and connected to another of said lines at a point between said pulleys so that tension will be maintained on all of the lines regardless of the 50 tilting of the bar as it is moved to extend the lines.
- 55 9. A portable clothes line unit comprising a coil spring secured at one end to a first end member fixed against rotation and at its other end to a rotatable member, a winding drum secured to said rotatable member for 60 rotation therewith and having a plurality of lines secured in spaced apart position on its surface, said rotatable member being rotatably supported at one end by a second end member and said drum being rotatably supported at its other end by said first end member, and means connected with said rotatable member for rotating said drum and for locking said drum in any desired position.
- 65 10. A portable clothes line unit comprising a rotatable drum, a rotatably mounted member secured to one end of said drum and a fixedly mounted member rotatably connected to the other end of said drum, a coiled spring interconnecting said rotatably mounted member with said fixedly mounted member for biasing said drum to rotate in one direction, a plurality of lines each having one end secured to said drum and the other end extendable from the drum, means for securing said lines in extended posi-

tion, means connected with said rotatably mounted member for rotating said drum to tighten said lines after said lines have been secured in extended position, and means for locking said rotating means after said lines have been tightened by said rotating means.

11. A portable clothes line unit as defined in claim 10, wherein said locking means comprises a stationary end member for rotatably supporting said rotatably mounted member and positioned adjacent said rotating means and having a series of spaced openings, and pin means carried by said rotating means and movable into locking engagement with one of the openings in said end member.

12. A portable clothes line unit comprising a first stationary end member, a rotatable member, a spring secured at one end to said first stationary end member and at its other end to said rotatable member, a winding drum secured to said rotatable member adjacent an end thereof and rotatably supported on said stationary end member adjacent the other end thereof, said drum carrying a plurality of lines, means for holding the lines in extended position, a lever pivoted to said rotatable member for tightening said lines after the lines have been extended, and means for locking said lever in position after said lines have been tightened, said spring means exerting a force on said drum to wind the lines upon the drum after the lines have been released from said holding means and the locking lever released.

13. In a portable clothes line unit, a single member for mounting a plurality of lines in spaced apart relationship, means for rotatably mounting said member, one end of each line being secured to said member and the other end of each line being extendable away from said member, and a second member carrying a pulley for each of said lines with said pulleys being spaced apart on said member, said other ends of two adjacent lines being joined together around an adjacent pair of pulleys to provide at least one integral pair of lines, the tension on said lines being maintained while said lines are being extended regardless of any tilting of said second member relative to the first-mentioned member.

14. In a portable clothes line unit as defined in claim 13, means for pivotally mounting said second member to hold said lines in extended position, said pulleys and said mounting means permitting the load on one line to be distributed among the other lines.

15. A portable clothes line unit comprising a spring connected at one end to a fixed member and connected at the other end to a rotatable member, a winding drum rotatably mounted at one end on said fixed member and fixed at the other end to said rotatable member, a plurality of lines secured in spaced apart position on the surface of said drum, an equalizer bar carrying a series of pulleys equal in number to the number of lines and spaced apart the same distance as the lines on the drum, each line

passing around one of said pulleys and being connected to an adjacent line substantially midway between the pulleys for the two lines, a support member mounted at a point remote from said drum, and means for pivotally mounting said equalizer bar on said support member when extended so that an excessive load on one line can be distributed to the other lines.

16. A portable clothes line unit comprising a spring connected at one end to a fixed member and connected at the other end to a rotatable member, a winding drum rotatably mounted at one end on said fixed member and fixed at the other end to said rotatable member, a plurality of lines secured in spaced apart position on the surface of said drum, an equalizer bar carrying a series of pulleys equal in number to the number of lines and spaced apart the same distance as the lines on the drum, each line passing around one of said pulleys and being connected to an adjacent line substantially midway between the pulleys for the two lines, a casing surrounding said spring and said drum, said casing having an opening for receiving one side of said bar, and said drum being biased by said spring when said lines are in fully retracted position to hold said bar within said opening.

17. A portable clothes line unit comprising a plurality of lines secured in spaced apart position on a winding drum, said winding drum having a support member axially fixed in one end of said drum and a support member rotatably supported in the other end of said drum, biasing means interconnected with each of said support members for biasing said drum to rotate in one direction, means connected with the first-mentioned support member for rotating said drum and for locking said drum in any desired position, a bar having a pulley for each of said lines with said pulleys spaced apart substantially the same distance as the lines, each of said lines passing around one of said pulleys and connected to another of said lines at a point between said pulleys, a support means fixed at a point remote from said drum, and means for pivotally mounting said bar with said support means whereby said bar can pivot sufficiently to equalize any excessive load on any one or more of the lines.
